CLAIM

The ornamental design for a deer antler rattle call, as shown and described.

DESCRIPTION

FIG. 1 is a perspective view of the deer antler rattle call; FIG. 2 is a front view of the deer antler rattle call; FIG. 3 is a rear view of the deer antler rattle call; FIG. 4 is a first side view of the deer antler rattle call; FIG. 5 is a second side view of the deer antler rattle call; FIG. 6 is a bottom view of the deer antler rattle call; and, FIG. 7 is a top view of the deer antler rattle call.

The broken lines in the drawings depict portions of the deer antler rattle call that form no part of the claimed design.
